UNITED STATES PATENT OFFICE.

JOHN A. THORNTON AND WALTER A. SETTLE, OF WALLA WALLA, WASHINGTON,
ASSIGNORS OF ONE-THIRD TO FRANCES B. ALLEN, OF WALLA WALLA, WASHINGTON.

CAMP-TABLE.

1,155,971.

Specification of Letters Patent.

Patented Oct. 5, 1915.

Application filed June 10, 1914. Serial No. 844,282.

To all whom it may concern:

Be it known that we, JOHN A. THORNTON and WALTER A. SETTLE, citizens of the United States, residing at Walla Walla, in the county of Walla Walla and State of Washington, have invented certain new and useful Improvements in Camp-Tables; and we do hereby declare the following to be a full, clear, and exact description of the invention, such as will enable others skilled in the art to which it appertains to make and use the same.

This invention relates to camp tables and has for an object to provide a table of improved construction with improved means for folding and rolling into compact form.

A further object of the invention is to provide improved means for supporting the fabric top of the table.

A further object of the invention is to provide improved means for temporarily securing the legs in operative position.

A further object of the invention is to provide improved means for expanding the table top and holding the fabric taut.

With these and other objects in view the invention comprises certain novel constructions, combinations and arrangement of parts as will be hereinafter more fully described and claimed.

In the drawings, Figure 1 is a view of the improved table in perspective. Fig. 2 is a view of the improved table in inverted plan. Fig. 3 is a longitudinal sectional view of the table taken on line 3—3 of Fig. 2. Fig. 4 is an inverted plan view of the table showing the legs folded and the center brace rotated to longitudinal position. Fig. 5 is a perspective view of the table rolled. Fig. 6 is a detail perspective view of one of the ends of one of the supporting braces. Fig. 7 is a detail perspective view of one of the extremities of one of the end pieces. Fig. 8 is a fragmentary perspective view of one end of the table with a slightly different modification of leg fastening means. Fig. 9 is a fragmentary end view of the table showing the leg fastening means disclosed at Fig. 8. Fig. 10 is a fragmentary sectional view taken on line 10—10 of Fig. 9.

Like characters of reference designate corresponding parts throughout the several views.

The improved camp table which forms the subject matter of this application comprises

side rails 10 and end rails 11, the latter being hinged to one of the side rails by the hinges 12. Rails 11 are so mounted as to be spaced from the side rails when folded parallel therewith, providing spaces for the leg members described below. At the ends opposite the hinges the end rails 11 are provided with stirrups 13 proportioned to fit over the extremities of the opposite side rail 10 so that when the end rails 11 are expanded to operative position and the stirrups 13 engaged over the extremities of one of the said side rails 10 the rails form a substantially rectangular frame. The end rails 11 are also provided with a plurality of notches 14 cut in their top surfaces as shown more particularly in perspective at Fig. 7 and a plurality of longitudinal braces 15 are provided having cut out portions at the end as indicated at 16 in Fig. 6 to engage over the uncut portion of the end rails 11 and presenting a shoulder 17 which abuts against such rail and carrying a hook or angle member 18 which engages over the exterior of the side rails 11 as indicated more particularly at Figs. 1 and 3. A recess of U-shape is formed between the upturned portion of member 18 and the inner wall of the cut-away portion at the end of the brace, as shown in Fig. 6. This recess engages the end rail and movement of the parts in either direction is prevented. It will be apparent that with a number of such longitudinal braces extending between the end rails 11 the fabric 19 secured to the side rails 10 and the longitudinal braces 15 will be supported on a plurality of lines. The fabric will also preferably be secured in such position as by the use of nails 20 inserted into both the side rails and the longitudinal braces 15.

The central longitudinal brace carries a transverse brace 21 pivoted intermediate its length at 22 proportioned to swing from a position in parallelism with said brace to a position transverse of the table and engaging at its opposite ends the opposite side rails 10 to force them apart and augment the stretching of the fabric 19.

The table top thus composed is supported by legs 23 pivoted to the side rails as at 24 with stops 25 secured to said side rails in any approved manner as by the bolt 26. The legs 23 are movable upon their pivots 24 from the supporting or operative position as shown

in Fig. 1 at which position they are engaged against the stops 25 to the inoperative position as shown at Fig. 4. To hold such legs in operative position eyes 27 are secured intermediate the ends of the said rails 11 and hooks 28 are pivotally secured to the legs as indicated at 29 and proportioned to engage the eyes 27. The hooks 28 may be made adjustable by a series of holes in the end 11 which may be bored at a slight angle from side to center and the rod sprung as the hook 28 is inserted thus locking it in the hole, or the same may be made adjustable by making the brace with a turn buckle 30, or by employing a spring 31, as shown in Fig. 3. It is obvious that with any of these means for exerting tension the hooks 28 when engaged in the holes in the end 11, or in the eyes 27 will serve to hold the legs 23 in operative position until released by unhooking such hooks.

With the table assembled in operative position as shown at Figs. 1 and 2 it may be knocked down by first releasing the hooks 28 from the eyes 27 and folding the legs inwardly as shown at Fig. 4. The transverse brace 21 is also turned from the position as shown at Fig. 2 to the position shown at Fig. 4 when the entire supporting portion 30 is folded within the lines of the top and may be transported in that condition if circumstances make it desirable. The table may be, however, further compacted by releasing the stirrups 13 from the extremities of the side rails 10 and the braces 15 lifted out from engagement with the end rails 11 whereupon the end rails may be folded in as shown in dotted lines at Fig. 4 and the entire top or cover is free to be rolled around the longitudinally extending sticks to form the package shown at Fig. 5. It may then be held in position by any approved manner, one means being shown as the cords 32. It is also obvious that in setting up the table the reverse of the above process is employed.

We claim:

1. A camp table comprising a frame composed of side rails and end rails hinged to

one of the side rails, said end rails being provided with notches cut in their top surfaces; braces extending longitudinally between the end rails, said braces having a right angled cutaway portion at each end and an angle member secured to each end to provide with said cutaway portion a U-shaped recess, the angle members engaging the notches in the end rails; and a fabric secured to the side rails and the longitudinal braces and adapted to roll about the rails and braces. 60

2. A camp table comprising a top embodying side rails and end rails hinged to one of said side rails and arranged to be folded parallel therewith and spaced therefrom, folding supporting members connected with the side rails and arranged to be placed at times parallel therewith and to lie between the folded end rails and the side rails; a separable fastener for the junction of the end rails with the side rail opposite the hinges; longitudinal braces extending between the end rails; and a fabric cover secured to the side rails and the longitudinal braces. 65

3. In a camp table, a frame comprising 75 side rails, an end rail hinged to each end of one of the side rails and arranged to be folded parallel with the side rail and spaced therefrom, leg members pivoted to the side rails and arranged to be folded parallel 80 therewith, certain of the leg members being adapted to lie between one side rail and the folded end rail, means for connecting the leg members with the end rails, braces connecting the end rails, means on the end of 85 each brace for engaging opposite sides of the adjacent end rail, and stirrups on one end of each end rail for engaging the adjacent end of one of the side rails.

In testimony whereof we affix our signatures in presence of two witnesses. 90

JOHN A. THORNTON.

WALTER A. SETTLE.
